FLUSHING TANK FOR SIPHON CLOSETS,
APPLICATION FILED JAN. 22, 1919. RENEWED APR. 30, 1921.

1,382,028.

Patented June 21, 1921.

UNITED STATES PATENT OFFICE.

JOHN S. SWEENEY, OF GALVESTON, TEXAS.

FLUSHING-TANK FOR SIPHON-CLOSETS.

1,382,028.

Specification of Letters Patent. Patented June 21, 1921.

Application filed January 22, 1919, Serial No. 272,526. Renewed April 30, 1921. Serial No. 465,924.

To all whom it may concern:

Be it known that JOHN S. SWEENEY, citizen of the United States, residing at 3127 Avenue O, Galveston, in the county of Galveston and State of Texas, has invented certain new and useful Improvements in Flushing-Tanks for Siphon-Closets, of which the following is a specification.

This invention relates to improvements in 10 flushing tanks for siphon-closets.

The primary object of the invention is to provide improved means for creating a partial vacuum to siphon the water for flushing purposes, whereby to insure of the continued 15 action of the parts.

A further object of the invention is to provide improved means for destroying the partial vacuum to prevent the siphon action of the water destroying the trap or seal, and 20 to also render the action of the water noiseless.

The invention also provides improved means for quickly and accurately closing the inlet valve when the water reaches the required level in the tank.

The invention also comprehends improvements in the details of construction and arrangement of parts which will be hereinafter described and particularly pointed out 30 in the claims.

In the drawings:

Figure 1 is a perspective view of my improved flush tank.

Fig. 2 is a central vertical section of the 35 same.

Fig. 3 is an enlarged sectional view of the upper end of the shell and plunger, the full lines showing the position of the parts when forming a partial vacuum to flush the tank, 40 and the dotted lines showing the position of the same parts when at rest.

1 indicates a tank, through the bottom of which extends a pipe section 2, into which fits a flushing pipe 3. The flushing pipe 45 3 is suitably coupled to the pipe section 2 and below the tank it is formed with a trap 4.

Surrounding the pipe section 2 and spaced therefrom is a cylindrical stationary shell 50 5, from the upper end of which depends a short pipe 6, of less diameter than the pipe section 2 and depending into the latter and terminating below the plane of the greatest level of the water in the tank, the shell 55 being supported on the pipe 2, by spiders 5a.

On top of the shell above the pipe 6, is a

valve seat 7 which receives a disk valve 8 provided with a small vent opening 9. A cage 10 surrounds the valve 8, to retain same in position, in the operation of the apparatus. 60

A cylindrical hollow plunger 12 fits over the shell 5, and is provided with a hollow projection 13 to inclose the cage 10. In the top of the plunger 12 is a valve seat 14, to receive a disk valve 15, and fitting over same 65 is a cage 16 to retain the valve in place. 17 indicates a stud which extends from the top of the shell 5, and engages the valve 15 when the plunger is lowered, to insure of the valve being removed from its seat, 70 for a purpose which will presently appear.

An operating lever 18 is fulcrumed at 19, and at its end it is provided with a pull chain 20, to flush the closet, the opposite end of the lever engaging under a yoke 21 75 on the hollow projection 13.

Tapped in the upper neck of the trap 4 is one end of siphon pipe 23, which extends up through the tank and above the normal water level indicated by the dotted line 22, 80 and extends downwardly and terminates just above the level of the water in the tank after the flushing operation has taken place. The purpose of this pipe is to admit air to the trap about at the time the water reaches the 85 lowest level, to destroy the partial vacuum in the shell, and thereby prevent the destruction of the seal in the trap.

The normal level of the water in the tank 1 is indicated by the dotted line 22, and when 90 the lever 18 is operated the plunger 12 is raised, the movement of the plunger being guided by the shell 5, and the snug fit of the parts serving as a means to prevent water being drawn in between the joints to any appreciable extent. When the plunger is elevated, a partial vacuum is created. This action raises the valve 8, and the partial vacuum is extended to the space in the shell 95 above the normal level of the water, and of course in the section of pipe 2. The lifting of the plunger draws the air through the section of the pipe 2, and the space in the upper end of the shell causing the water 100 to flow over the top of pipe 2, which precludes the suction of water into the space between the plunger and shell. In other words by terminating the pipe 6 at a point below the top of the pipe 2, the partial 110 vacuum is formed before the water flowing over the pipe 2 reaches the end of pipe 6.

This, it will be seen effectually prevents the water being drawn through the pipe 6 and above the shell.

If the pipe 6 were omitted the current 5 of air flowing through the opening in the valve seat 7 would be upward and would tend to draw the water in that direction; and a sudden lifting of the plunger might cause water to splash upward into the space above 10 the shell. By providing the pipe 6, it will be seen that the vacuum above the shell draws air from the pipe section 2 at the lower end of pipe 6, thus causing a downward current 15 of air in the upper portion of the pipe section 2, which would prevent the above mentioned splashing.

In the operation of the plunger, the vent opening 9 in the valve in no way affects the formation of the partial vacuum. However, 20 should the elevation of the plunger be only sufficient to balance the parts and create sufficient vacuum to cause the water to flow, but not flush, the air admitted through the valve 15, previously opened by the stud 17, 25 between the plunger and the shell will vent through the opening 9, in the now seated valve 8, and thus destroy the partial vacuum within the shell and thereby stop the running of the water, and cause the parts to assume 30 their normal position.

After the plunger 12 is elevated, the pull on the chain is released, the plunger lowers of its own weight, and the valve 8 is lowered on its seat, while the valve 15 is opened to 35 release air between the shell and plunger. If, as previously mentioned, water should have found its way above the shell when the tank was flushed, this water will be gradually forced through the opening controlled 40 by the valve 15 when the plunger is lowered.

While it is preferred that the valves 8 and 15 be employed for the purposes described, yet it will be apparent from the previous description and illustration that 45 the use of these valves is not absolutely essential. For example, assume the plunger without openings, it will be understood that as the plunger is elevated, it will tend to draw air from the space within the stationary shell 50 and above the water line, through the restricted pipe 6, thus tending to create a vacuum within the shell sufficient to raise the water level above that of the pipe section 2 and start the siphonic action. As the 55 water flows by the lower open end of the pipe 6, it will obviously draw the air from between the shell and plunger downwardly through the pipe 6 and carry it off with the water flowing to the flush. Thus the air 60 withdrawn from the stationary shell to start the siphon will be taken from the plunger through the pipe 6 and carried off with the moving column of water. Thus the air is disposed of while the water in the tank has 65 a head above the outlet of the pipe 6, and

therefore this air is without effect on the siphonic action. It will be understood that air coming from the bottom end of pipe 6 cannot kill the siphonic action as long as the head of water in the tank is above the bottom 70 end of pipe 6, and therefore the air in the shell will have been substantially exhausted before the water head in the tank is lowered to the bottom end of the pipe 6. Thus the relief valves proposed are not absolutely 75 essential as with the restricted pipe 6 arranged as shown, the action will be properly completed.

It is not absolutely necessary that the vent 80 opening be in the valve 8. The vent may be in any point in the top of the shell so long as it communicates with the short pipe 6, to provide an uninterrupted conduit for the free passage of air to destroy the partial 85 vacuum in the shell if it should happen that sufficient movement of the plunger is not imparted when the chain is pulled.

At or about the time the water in the tank reaches the lower level, indicated by the dotted line 30, after the flushing operation has 90 taken place, it is of course necessary to prevent destruction of the water seal in the trap. This is taken care of by the siphon pipe 23. Air rushes in the lower end of the siphon pipe, and the effect of the partial 95 vacuum in the pipe section 2 is destroyed, since the momentum of the head of water in the flush pipe beyond the trap draws air through the siphon pipe, and promptly the pressure of the vacuum on the water in pipe 100 2 is destroyed. It therefore follows that the partial vacuum in pipe 2 cannot act to force the water from the trap and destroy the seal, and render the apparatus unfit for the succeeding operation. 105

In addition to the siphon pipe serving the purpose described, it also acts to provide an additional supply of water for flushing purposes. When the tank is flushed, the "pull" 110 of the water in passing through the flush pipe, siphons water through the siphon pipe, as will be obvious.

I have found that by varying the height of the free end of the siphon pipe with reference to the lower water level, the noise 115 usually incident to a flushing operation, can be largely eliminated. Therefore it is my purpose to arrange the pipe section 31, so that it can be adjusted to suit the lower water level to prevent the noise when flushing. This adjustment may be accomplished by threading the lower end of the pipe 23, in the trap, as shown at 23^a in Fig. 1.

The vent opening 9 in the valve 8, as previously stated, serves to produce a most important result, and one which is vital in a structure of this general type. If in pulling the chain, the operator should not raise the plunger sufficiently to flush the tank, it would produce an equalization or balancing 130

of the siphoning of the water, and the action 5 of the plunger. In this event the siphon action set up would just barely be sufficient to raise a constant leaking or flowing of the water through the flush pipe, and lower the water a trifle in the tank and thereby partially open the valve, a condition which cannot be destroyed without the destruction of the partial vacuum set up. Should this 10 condition arise in my apparatus, the air passing through the vent opening will in a short time be quite sufficient to destroy the partial vacuum in the shell, and thereby permit the parts to assume normal position, and prevent 15 leakage or constant waste of water.

What I claim is:—

1. In a flushing apparatus, the combination of a tank, a shell in the tank and open at the bottom, a flush pipe extending into 20 the shell, a short pipe extending from the top of the shell and extending into the flush pipe and terminating below the plane of the top of the latter, a valve on top of the shell for controlling the inlet end of the short 25 pipe, a hollow plunger fitting over the shell, a valve in the top of the plunger for admitting air between the plunger and shell when the plunger is lowered, means for raising the plunger to produce a partial vacuum in the 30 shell to cause the water in the tank to be siphoned through the flush pipe, the valve on the shell opening when the plunger is raised, and means for automatically replenishing the tank with water.

35 2. In a flushing apparatus, the combination of a tank, a fixed flush pipe extending up into the tank, and provided with a trap, a fixed inverted shell over the free end of the flush pipe, a valve in the top of the shell, 40 said valve having a constantly open vent, a short pipe depending from the shell and extending into the upper end of the flush pipe, a hollow plunger fitting over the shell, a valve in the top of the plunger, and means 45 for elevating the plunger, the valve in the shell opening and the valve in the plunger closing when the plunger is elevated, whereby a partial vacuum is formed in the shell, the vent opening admitting air to the 50 interior of the shell and gradually destroying the partial vacuum in case the plunger is not moved sufficiently.

55 3. In a flushing apparatus, the combination of a tank, a fixed flush pipe extending up into the tank, the flush pipe having a trap, an inverted shell fitting over the top of the flush pipe, a short pipe depending from the top of the shell and extending into the flush pipe, a valve for controlling the 60 passage through the short pipe, and normally opening outwardly, a hollow plunger fitting over the hollow shell, and a valve in the stop of the plunger, said valve normally

opening when the shell is lowered, means for elevating the plunger to form a partial vacuum in the shell to cause the water to be siphoned from the tank, a siphon pipe communicating with the top of the trap and terminating at or near the lower water level in the tank, whereby to destroy the partial vacuum in the shell after the tank is flushed.

70 4. In a flushing apparatus, the combination of a tank, a fixed flush pipe extending up into the tank, the flush pipe having a trap, an inverted shell fitting over the top of the flush pipe, a short pipe depending from the top of the shell and extending into the flush pipe, a valve for controlling the 75 passage through the short pipe, and normally opening outwardly, a hollow plunger fitting over the hollow shell, a valve in the top of the plunger, said valve normally opening when the shell is lowered, means for elevating the plunger to form a partial vacuum in the shell to cause the water to be siphoned from the tank, a siphon pipe 80 communicating with the top of the trap, the free end of said pipe terminating at or near the lower water level in the tank, whereby to noiselessly destroy the partial vacuum in the shell after the tank is flushed.

85 5. In a flushing apparatus, the combination of a tank, a fixed flush pipe extending up into the tank and provided with a trap, a fixed inverted shell over the free end of the flush pipe, a short pipe depending from the shell and extended into the flush pipe 90 below the top level of the same, a valve for controlling the upper end of the short pipe, a hollow plunger fitting over the shell, a valve in the top of the plunger, the valve in the shell opening and the valve in the 95 plunger closing when the plunger is elevated, whereby a partial vacuum is formed in the shell, and means for maintaining a constant passage for the admission of air to the shell to prevent the continuation of a 100 partial vacuum after the plunger is operated.

105 6. In a flushing apparatus, the combination of a tank, a shell in the tank and open at the bottom, a flush pipe extending into the shell, a hollow plunger fitted over the shell and operative to cause a partial vacuum in the shell on the outward movement of such plunger relative to the shell, means for operating the shell, and a short pipe of 110 comparatively restricted bore carried by and opening through the shell, said pipe terminating in an open end within the flush pipe below the normal level of water in the tank.

120 In testimony whereof I affix my signature.

JOHN S. SWEENEY.
